UNITED STATES PATENT OFFICE

NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA

TRANSMISSION-LINE DEVICE

Application filed August 11, 1927. Serial No. 212,195.

- My invention relates to transmission-line devices and particularly to electrostatic-field-controlling means, such as arcing rings, for association with suspension clamps.
- 5 One object of my invention is to provide a device of the above-indicated character that shall comprise a single means for clamping a conductor and mounting an electrostatic field-controlling element relative thereto.
- 10 Another object of my invention is to provide an electrostatic shielding ring that shall have relatively great surface area on its longitudinal sides surrounding a suspension clamp.
- 15 Another object of my invention is to provide a field-control ring that shall comprise few parts and that shall greatly facilitate its manufacture and assembly.
- Another object of my invention is to provide a field-control or arcing-ring device that may be readily mounted in operative position around an insulator, while the latter is mounted in operative relation to a conductor and to a supporting tower with which it is 20 associated.
- Another object of my invention is to provide a field-control ring that shall be simple and durable in construction, economical to manufacture and effective in its operation.
- 25 In high-voltage insulator practice, it is usual to mount an annular or ring-like electrostatic-field-controlling device around the insulator for keeping ultimate arc-over free of the dielectric parts.
- 30 However, as simple as a ring with inwardly extending supporting arms may seem to be in this field, by reason of its relatively great diameter, compared to the cross-section of the stock from which it is constructed, and
- 35 because of the effects of the service for which it is adapted, an entirely satisfactory and effective ring of this character and for this service is sometimes difficult and expensive to manufacture.
- 40 Violent vibrations of the line may so distort or displace the arc-assuming portion of the ring as to render it useless, if not detrimental to the line.
- 45 Adjacent metal parts, such as the ends of projecting lugs, pins and bolts, also some- times interfere with the operation of the rings by causing greater concentration at local points thereon or by attracting the field away therefrom.
- Further, where the parts of such a ring are 55 permanently and integrally united, the insulator around which it is to be mounted must be detached from the tower or conductor, with which it is associated, for the reception of the ring.
- It is my aim to overcome all of the above-mentioned objections, and, accordingly, in practicing my invention, I provide a structure that is constructed of simple sheet material elements that are adapted for mounting on a suspension clamp by the clamping means thereof, and that has other features of advantage to materially facilitate and economize its manufacture, cause it to be 60 self-braced against distortion, render its assembly and mounting simple and expeditious operations and permit it to effectively shield the clamp.
- 65 Figure 1 of the accompanying drawings is a side view, partially in elevation and partially in section, of a device constructed in accordance with my invention, and
- 70 Fig. 2 is a top plan view of the device shown in Fig. 1.
- 75 A clamp 2, of the usual well known construction, comprises a conductor-receiving or channel portion 3 having an upwardly extending suspension or clevis portion 4 thereon, a clamping shoe member 6 and J-bolts 7 and nuts 8 or equivalent fastening means for 80 clamping a conductor 9 in the channel member 3.
- An electrostatic-field-controlling device 10, of my invention, comprises an annular element 12 constructed of half sections 14 of 85 sheet material of substantially uniform cylindrical shape, and of relatively great width or height to effectively cover or enclose the clamp 2.
- A supporting member 15, also constructed 90 of sheet material of relatively great width and area, is constructed to be of substantially U-shape, having free ends or legs 16, substantially conforming to the inner cylindrical surfaces of the element 12, and an 95
- 100

apertured intermediate portion 17 for mounting on the channel member 3, by the bolts 7.

The legs 16 are preferably disposed with their upper edges below the upper edges of the element 12 and the outer surfaces thereof against the inner surfaces of the adjacent halves 14. The element 12 and the member 15 are preferably of sufficient width to readily adapt the structure for the reception of a plurality of standard bolts 18 well within the edges of the members 14 and 15 for holding the same together.

In the above-described structure, constructing the elements 14 and 15 of simple sheet stock, and connecting them to each other and to the clamp 2 by the standard bolts 7 and 18, renders the device of extremely simple and economical manufacture, reduces the number of parts to substantially a minimum and renders assembly and mounting of the device extremely easy.

By having the half portions 14 detachably secured to the supporting member 15 in the manner shown, the device may be readily mounted on the clamp 2, while the latter is mounted in operative position on an insulator.

While I have shown and described a particular form of my invention, changes may be effected therein without departing from the spirit and scope thereof as set forth in the appended claims.

I claim as my invention:

1. In a transmission-line device, the combination with a clamp including a conductor-receiving member and a member for clamping the conductor relative thereto, of an electrostatic-field-controlling element comprising a multi-part arc-assuming member and a member held in position by said clamping member for holding said arc-assuming parts together.

2. In a transmission-line device, the combination with a clamp including a conductor-receiving member and a member for clamping the conductor relative thereto, of an electrostatic-field-controlling element comprising a halved annular arc-assuming member and a member held in position on the clamp by said clamping member and secured to each of said halves for holding the same together.

3. In a transmission-line device, the combination with a clamp including a conductor-receiving channel member and a plurality of bolts for clamping the conductor relative thereto, of an electrostatic-field-controlling element comprising a halved annular arc-assuming member and a supporting member secured to the channel member by said bolts and secured to each of said halves in removable relation to one thereof.

4. A transmission-line device comprising an arc-assuming element of sheet material of substantially uniform cylindrical shape and an independently-formed supporting mem-

ber therefor of sheet material extending between, and secured to, substantially diametrically-opposite positions thereon.

5. A transmission-line device comprising an arc-assuming element of sheet material of substantially uniform cylindrical shape and an independently-formed supporting member therefor of sheet material of substantially U-shape extending between and secured to substantially diametrically-opposite positions thereon, the legs of the U being shaped to substantially conform to the cylindrical side surfaces of the annular arc-assuming element.

6. A transmission-line device comprising an arc-assuming element of sheet material of longitudinally-halved substantially uniform cylindrical shape and an independently-formed supporting member therefor of sheet material of substantially U-shape extending parallel to the diameter dividing said halves and having each of its free ends secured to adjacent ends of said halves.

7. A transmission-line device comprising an arc-assuming element of sheet material of longitudinally-halved substantially uniform cylindrical shape and an independently-formed supporting member therefor of sheet material of substantially U-shape extending parallel to the diameter dividing said halves and having each of its free ends secured to the sides of adjacent ends of said halves.

8. A transmission-line device comprising an arc-assuming element of sheet material of longitudinally-halved substantially uniform cylindrical shape and an independently-formed supporting member therefor of sheet material of substantially U-shape extending parallel to the diameter dividing said halves and having each of its free ends secured to inner sides of adjacent ends of said halves below the upper edges thereof.

In testimony whereof, I have hereunto subscribed my name this 4th day of August, 1927.
